UNITED STATES PATENT OFFICE.

JARED G. DAVIS, OF LEE, MASSACHUSETTS.

DESIGN FOR A FEED-TROUGH.

SPECIFICATION forming part of Design No. 23,396, dated June 19, 1894.

Application filed May 16, 1894. Serial No. 511,484. Term of patent 14 years.

To all whom it may concern:

Be it known that I, JARED G. DAVIS, a citizen of the United States, residing at Lee, in the county of Berkshire and State of Massachusetts, have invented and produced a new and original Design for Feed-Troughs, of which the following is a specification, reference being had therein to the accompanying drawing.

- 10 The drawing represents a perspective of the feed trough having my design. The leading feature of the design consists in the upright eccentric curved surfaces 1 and 2 united at their extremities by the upright 15 plane surfaces 3 and 4, in connection with the upright plane surfaces 5 and 6 extending from the curved surfaces 2 and converging to the rear to a point where they meet thus presenting the figure or shape of a quadrant.

Another feature of the design is the plane 20 horizontal surfaces 7 and 8 extending from the ends of the front curved surface 1 to and meeting the vertical plane surfaces 3 and 4 which unite with said curved surface 1 at its ends. The lid 9 likewise has the outline of a 25 quadrant.

The numeral 10 designates bars running at right angles to the curved surfaces 1 and 2 and merging at their ends into said surfaces.

What I claim is—

30 The design for a feed trough herein shown and described.

In testimony whereof I affix my signature in presence of two witnesses.

JARED G. DAVIS.

Witnesses:

WILLIAM H. HARRIS,
PAUL R. TOWNE.
